DESIGN FOR A COMBINED CONTAINER AND DISPENSING UNIT FOR FLINTS OR THE LIKE

Jacques Schwalbe, New York, N. Y.

Application March 28, 1940, Serial No. 91,299

Term of patent 7 years

To all whom it may concern:

Be it known that I, Jacques Schwalbe, a citizen of Belgium, residing at the city, county, and State of New York, have invented a new, original, and ornamental Design for a Combined Container and Dispensing Unit for Flints or the like, of which the following is a specification, reference being had to the accompanying drawing, forming part thereof.

Figure 1 is a perspective view of the article, showing my new design;

Figure 2 is a rear elevational view; and
Figure 3 is a side elevational view.
The cover is made of transparent material.

I claim:

The ornamental design for a combined container and dispensing unit for flints or the like, substantially as shown and described.

JACQUES SCHWALBE.
